Letters Patent No. 3015-Dated Dec 18-1864.

Design for a Stove Plate.

the schedule referred to in these Letters Patent and making part of the same.

Is all whom it may concern:

Be it known that we, Nicholas S. Videlier, and Ezra Ripley, each of the City of Troy, in the County of Rensselaer and State of New York, have jointly invented or produced a certain new and original ornamental Design for Stove Plates; and we do hereby declare that the following is a full, clear and exact description of the same, reference being had to the accompanying photograph of a stove plate having our said ornamental design.

This ornamental design consists of a cushion-like panel, having a border A and depressed ornamental bands B, crossing each other at right angles, with a large rosette C at each crossing, and dividing the panel into several swelling smooth surfaces parts D, each having a smaller rosette in its middle; the whole, so shaped and arranged, and cast on a stove plate, as to present an appearance like the aforesaid accompanying photograph.

What we claim as new and of our invention is the above described ornamental design for stove plates.

In testimony whereof we hereunto subscribe our names this 13th day of November, 1864.
